UNITED STATES PATENT OFFICE.

OSBORN B. HALL, OF MALDEN, MASSACHUSETTS.

FIRE-LADDER.

SPECIFICATION forming part of Letters Patent No. 536,381, dated March 26, 1895.

Application filed May 7, 1894. Serial No. 510,316. (No model.)

To all whom it may concern:

Be it known that I, OSBORN B. HALL, of Malden, in the county of Middlesex and State of Massachusetts, have invented a new and useful Improvement in Fire-Ladders, which will, in connection with the accompanying drawings, be hereinafter fully described, and specifically defined in the appended claims.

In said drawings: Figure 1 is a side elevation of my ladder truck, as arranged for movement through the streets, the forward part of the pole and a portion of the front or upper part of the ladder being broken away in order to gain room on the sheet. Fig. 2 is a rear or left hand end of Fig. 1. Fig. 3 is a top plan view of Fig. 1. Fig. 4 is a horizontal section taken on line x, x , Fig. 2, and viewed as from above said line. Fig. 5 is a sectional elevation, the section being taken on line y, y , Fig. 3, and the view as from the left in said Fig. 3. Fig. 6 is a detached enlarged rear elevation of the ladder, and showing the method of connecting one of the hoisting ropes therewith.

The object of my invention is to provide a ladder that is mounted upon wheels and can be transported quickly to the scene of fires; that when halted in place can by withdrawing the evener bolt be raised into position by the advancing movement of the horses that draw the truck; and the same force that is used to raise the ladder into position will be employed to move the top section upward into place; and it consists in the devices and the combinations thereof that will be next herein explained and then defined in the claims.

Referring again to the drawings, a, a represent the front wheels and b, b the rear ones. Said wheels a are arranged on front axle c and wheels b on rear axle d . The bed e extends from axle d to rocker f which is centrally pivoted to axle c . If desired, both axles c and d can be pivoted to the bed so as to admit of turning short curves, in a well known manner. Said bed e can be trussed as shown at g and to the desired extent to render it sufficiently rigid for its purpose.

Upon bed e are raised the rear uprights h and the front uprights i . Said uprights h are hinged to bed e and are supported by screw j on which is the centrally threaded hand wheel k that actuates standard l and thereby ad-

justs the standards h at the desired angle. Standards i also rise from bed e and are duly stayed by iron rods as shown.

The ladder is of course formed in two or more sections, the lower or main section being shown at m and it is bolted rigidly to plate n that is pivoted to standards h . Said section m can be guyed by rods q and when mounted on the truck its forward end extends a considerable distance in front of standards i . The movable section of my ladder is shown at t , which fits between the sides of part m and at the top of m is the wider piece 2 , between which and the rungs of part m part t of the ladder slides.

To the lower rung of part t is secured the hoisting rope 3 that passes up over sheave 4 arranged on bar 2 as shown, and thence it descends passing round sheave 5 and thence undersheave 6 , and thence to drum 7 to which its end is secured.

A cord 8 is attached to rings 10 that fit loosely upon the ends of the sides of ladder m (see Fig. 6) and passes down under sheave 9 at the rear end of platform e , and it passes thence under sheave 6 , and to drum 7 to which it is secured. If needed, in order to guide cords 3 and 8 onto drum 7 a fair leader sheave 11 can be employed. A rope 12 is wound upon drum 7 in a direction opposite to ropes 3 and 8 , and its end is secured to said drum, so that when it is running off of said drum at the bottom said cords 3 and 8 will be passing onto said drum at the same point. Said rope 12 leads forward and is secured to evener 13 , that is pivoted upon the pole 14 .

It will be apparent that when this ladder is drawn to the place where it is to be used, the driver has only to withdraw the bolt 15 on which evener 14 is pivoted, and to then urge the horses forward thereby drawing rope 12 forward and thereby rotating drum 7 in the direction indicated by the arrow in Fig. 1, thus drawing ropes 3 and 8 forward and winding them upon said drum, thereby raising both sections of the ladder and projecting section t upward. When the ladder is well but not fully raised the rings 10 by which rope 8 is attached to section m will slip therefrom and then the upward movement of the ladder will be continued by rope 3 .

It will be seen that one revolution of drum

7 will nearly or quite raise the ladder into place for use; and if it be found necessary ropes 3 and 8 can be arranged to wind upon a section of the drum less in diameter than 5 that on which rope 12 is wound; or ropes 3 and 8 can pass onto drum 7 and rope 12 can be wound upon another drum that drives a pinion that meshes in a larger gear attached to drum 7.

10 A pawl 16 is secured to bed *e* to engage circular rack 17 secured to said drum, to hold the ladder at any point in its ascent.

15 It will be apparent that my ladder can be moved quickly into position and that the raising it into position for use can be effected almost instantly as the horses can be detached from the carriage in the time required to draw pin 15 from the evener, and then the horses can be urged forward to raise the ladder, 20 which is quickly effected.

If desired a length of hose can be attached to section *t* and raised therewith so as to be in instant readiness when upraised to connect with hose leading from the hydrant or engine 25 to the ladder, and for use in playing upon the fire.

It is apparent that divers changes may be made in the details without affecting the spirit of my invention.

30 Having pointed out the nature of my invention, I will now proceed to claim it as follows, to wit:

1. The combination of wheel *n* arranged with its plane approximately in the vertical 35 longitudinal plane of the carriage that carries the ladder, and mounted upon a fixed

pivot arranged in the elevated frame *h*, *h*, *j*; and the ladder *m* rigidly bolted to said wheel and arranged to be elevated in a plane practically parallel with the longer line of the supporting carriage, substantially as specified. 40

2. The combination of the lower section *m* and the upper section *t* of the ladder, cord 8 attached to section *m* and cord 3 attached to section *t*, both said cords being connected 45 with drum 7, and thereby with evener 13, whereby the act of raising section *m* will impart an upward sliding movement to part *t*, substantially as specified.

3. In a fire escape the combination with 50 the section *m* mounted upon a fixed pivot and arranged to be elevated by an edgewise movement, in the longitudinal line of the supporting carriage, of the elevating cord 8 connected with drum 7 and connected with rings 10 55 loosely mounted on the lower end of said section *m*, for the purpose specified.

4. The combination of a ladder truck provided with the pivotal plate *n*, a ladder secured to said plate, section *t* arranged upon section *m*, ropes 3 and 8 attached to said sections passing thence over sheaves 6 and 9, and to drum 7 to which they are attached, and a rope 12 also attached to said drum and passing thence to evener 13 to which it is secured 60 whereby the horses by a forward movement can move said ladder to an upright position and can extend section *t*, as specified. 65

OSBORN B. HALL.
